UNITED STATES PATENT OFFICE.

JOHN W. UNGER AND HERMAN LAHANN, OF SIOUX CITY, IOWA.

DRINKING FOUNTAIN FOR STOCK.

Application filed January 20, 1920. Serial No. 352,827.

To all whom it may concern:

Be it known that we, JOHN W. UNGER and HERMAN LAHANN, are citizens of the United States, residing at Sioux City, in the county of Woodbury and State of Iowa, and have invented certain new and useful Improvements in a Drinking Fountain for Stock, of which the following is a specification.

This invention relates to a drinking fountain for stock of the type in which an overhead supply tank is employed which is so arranged with respect to the trough that, as the water is removed from the latter, an additional supply will be delivered thereto from the tank to maintain the level of the water in the trough at a predetermined point, the feed of the water taking place in accordance with the well known hydrostatic law.

The object of the invention is to provide a fountain of this character constructed to eliminate all screw caps, gates and like devices which would be liable to leak, bind or be inconvenient.

Another object is to construct a fountain of this character equipped with simple and efficient heating means which will maintain the water tepid, even in extremely low temperatures without over-working the lamps.

Another object is to provide a fountain of this character which exposes only a small quantity of water to the atmosphere, thereby preventing it from being unnecessarily chilled.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings:

Figure 1 represents a central vertical section of a fountain constructed in accordance with this invention; and

Fig. 2 is a horizontal section taken on the line 2—2 of Fig. 1.

In the embodiment illustrated, a water casing 1 is shown cylindrical in form, altho obviously it may be of any other desired cross section contour and has a heating chamber 2 in the bottom thereof in which is mounted a lamp 3 for supplying heat to

the fountain. This chamber 2 is equipped with a door 4 to afford access to the interior of the chamber, said door having apertures 5 therein for the passage of air to promote combustion. A trough 6, here shown substantially rectangular, is mounted above the heating chamber 2, the ends thereof being supported by outwardly and upwardly inclined extensions 7 of the combustion chamber, the trough having lateral fingers or lugs 8 resting on the upper ends of the extension and removably supporting the trough thereon.

The casing 1 is provided at diametrically opposite sides with inwardly inclined portions 9 which are arranged opposite the ends of the trough to afford ample room for the insertion of the animals' heads when they reach into the trough to drink therefrom. These inclined walls 9 extend to the bottom of trough 6, as shown clearly in Fig. 1, and form baffle plates, which are perforated, in the top of the water line, as shown at 10, for the purpose of excluding mud and sediment from the center of the trough.

Arranged within the casing 1 above trough 6 is a tank 11 of a size sufficient to provide ample space between its walls and that of the casing 1, so that the heated air from the combustion chamber 2 may pass up around the tank and out through an opening 23 in the top of casing 1, as will be presently more fully described. The bottom of this tank 11 has a funnel shaped nozzle 12 in which is mounted the lower end of a pipe 13 which extends centrally through the tank 11 and is apertured at its lower end, as shown at 14.

A rod 15 extends through pipe 13 and is provided at its lower end with a ball-shaped valve or stopper 17 designed, when the rod is lowered, to close the nozzle, the other end of said rod having a handle 16 which is adapted to be hooked over a bracket 18 when the fountain is in use.

A funnel shaped member 12^a extends upwardly from the upper end of pipe 13 above the top of the tank 11 and the bracket 18 is mounted in this funnel, as is shown clearly in Fig. 1.

The top 19 of the casing 1 is shown inclined upwardly toward its center, being removably mounted on said casing, and has an upstanding annular flange 20 around the central opening therein, which is closed by a removable cap 21, which cap has the air out-

let opening 23 in its apex. A hand grip 22 is preferably provided for removing the cap when it is desired to fill the fountain, as will be presently more fully described. An air space 24 is formed between the upper end of the funnel 12^a and the annular flange 20 of the casing top and affords communication between the aperture 23 and the air pipe in the sides of the casing.

10 An air pipe 25 extends from a point near the top of the tank 11 through the bottom thereof and terminates at the water level in the trough 6 and is designed to admit air to the tank when the water level in the trough falls so that the vacuum in the tank will be broken and the water flow out to the trough. When sufficient water enters the trough to seal the lower end of pipe 25, the flow of water will cease.

20 In the use of this fountain when it is desired to fill it, the handle 16 of rod 15 is disengaged from the bracket 18 and the ball-like valve 17 dropping into the nozzle 12 cuts off communication between the tank 25 and the trough. The cap 21 having, of course, first been removed, water is poured into the funnel 12^a and flows down through pipe 13 out through the perforation in the bottom thereof into the tank 11. When the 30 tank has been filled the handle 16 is again hooked over the bracket 18 to open the nozzle 12 and the water which is removed from the trough 6 will be supplied through this nozzle, in accordance with the well known 35 hydrostatic law.

The air entering the combustion chamber 2 through the apertures 5 is heated by the lamp 3 and passes up around trough 6 into the air space between the side walls of the 40 casing 1 and the tank 11 between the upper end of said tank and the top of said casing and passes out through the air chamber 24 and aperture 23 to the atmosphere, the heat by this time having been absorbed by the 45 water in the tank and in the trough, whereby said water is maintained sufficiently warm to render it palatable to the stock.

By providing the small cap 21 the heat 50 will be conserved during the filling of the fountain, since the vents are so arranged that a very small portion only of the heat will be permitted to pass out during the filling operation.

From the above description it will be ob-

vious that no screw caps, gates, or similar 55 devices are used, so that all danger of leakage is obviated and sticking or binding of the parts is also prevented.

The valve 17, above referred to, is preferably made of rubber, altho obviously it may 60 be of any suitable or desired material.

From the above description it will also be seen that owing to the small amount of water which is exposed in the drinking ends of the trough very little heat will be lost 65 from this source and yet ample room is provided for watering of the stock at these points.

Having thus fully described my invention, what I claim as new and desire to secure by Letters Patent, is:

A fountain of the class described comprising a casing having a combustion chamber in its lower end with a trough mounted above it, the top of said casing being provided with an opening surrounded with an upstanding flange, a removable closure adapted to be placed upon said flange, a water tank supported in said casing above said trough and being spaced from the walls 75 of the casing to provide a heat chamber around the tank, the bottom of the tank being provided with a funnel shaped depending nozzle having a valve seat therein, a vertical pipe extending through the tank and 80 having its lower end apertured and arranged in contact with the funnel shaped nipple of the tank and its upper end extended through the water tank and provided with a funnel shaped member which is arranged within 85 the flange of the top of the casing in slightly spaced relation thereto, a support arranged in said funnel shaped member, a valve stem extending through the vertical pipe and 90 having a valve on its lower end adapted to seat in the nozzle to cut off communication between the tank and trough when the former is being filled and the upper end of said stem being provided with means engageable with said support for retaining the valve off 95 100 of its seat.

In testimony whereof we affix our signatures in presence of two witnesses.

JOHN W. UNGER.
HERMAN LAHANN.
